UNITED STATES PATENT OFFICE.

LAURITS T. RASMUSSEN, OF COUNCIL BLUFFS, IOWA.

PACKING AND MULCHING IMPLEMENT.

1,132,118.

Specification of Letters Patent. Patented Mar. 16, 1915.

Application filed December 8, 1913. Serial No. 805,448.

To all whom it may concern:

Be it known that I, LAURITS T. RASMUSSEN, a citizen of the United States, residing at Council Bluffs, in the county of Pottawattamie and State of Iowa, have invented certain new and useful Improvements in Packing and Mulching Implements, of which the following is a specification.

This invention relates to a combined packing and mulching implement and has for one of its objects to provide such a construction that the mulching disk will operate as a scraper or cleaner for the packing disk.

Another object is to provide a mounting for the mulching disk which will operate to normally dispose its longitudinal axis rearwardly of the longitudinal axis of the packing disk so that the teeth of the mulching disk may enter the ground after the crest between the packing disks has been formed.

Still another object is to provide such a bearing or mounting for the mulching disk that both of these disks may be conveniently constructed, and of such form that they will sustain the stresses incident to their use without breakage or injury.

With these and other objects in view, the invention consists of the novel construction, combination and arrangement of parts as described herein and claimed, and as illustrated in the drawing, wherein,—

Figure 1 is a plan view of a combined packing and mulching implement embodying my invention. Fig. 2 is a partly broken view to illustrate the mounting of the mulching disks in the packing disks, and showing the relative position of parts. Fig. 3 is a sectional view on the irregular line 3—3 of Fig. 2, a shaft or axle being added.

Referring now to the drawing for a more particular description, numeral 4 indicates a shaft or axle, of any suitable length, having bearings at its ends in the elongated frame 5.

At 6 are indicated primary or packing disks mounted on the shaft so that they may rotate thereon, their hubs, spokes and rims being respectively indicated at a, b and c, the rims c being outwardly convergent or of substantially A-shape in cross-section. The inner surface of rims c provide circular bearing faces d preferably of uniform diameter as compared with each other, and

preferably each bearing-face d is disposed parallel with the longitudinal axis of the 55 disk.

At 7 are indicated secondary or mulching disks, each being carried by a packing disk and disposed between two adjacent packing disks. Each disk 7 consists of a sleeve 60 e of less diameter than disks 6, said sleeve having a contact-face f on its outer side and provided with an outwardly-projecting rim g with peripheral teeth h.

The frame may be provided with a suitable platform 8, the tongue and driver's seat being respectively indicated at 9 and 10, and it will be seen that the entire weight of the implement will be supported by the packing disks. During the forward movement of 70 the implement when drawn over a field, the weight of each mulching disk is the only force for causing its teeth to enter the ground, and these disks will normally project rearwardly of the packing disks during 75 this movement, as shown in Figs. 1 and 2, the longitudinal axes of said disks not being in alinement.

During the forward movement of the implement, the disks will rotate independently of each other and the rearmost part of the sleeve of each mulching disk will bear upon the rearmost part of the inner face d of the rim c of each packing disk. It will be understood that the ground will 85 be packed by operation of disks 6, longitudinal crests or ridges being formed between their rims, and the teeth of the mulching disks will form pockets or perforations in these crests, this being one of the desired 90 results in operation.

By referring to Figs. 1 and 2 it will be seen that disks 7 will operate as "self-cleaners" since the rearward part of these disks project rearwardly of disks 6, and the forward part of disks 6 may engage the sides of the teeth upon the forward part of disks 7, and this is a desired operation for causing adhesions to be removed from these parts.

The implement as described consists of 100 few and simple parts, and the disks may be conveniently constructed, the inner faces d of the packing disks and the outer faces f of sleeves e of the mulching disks preferably having smooth surfaces so that the 105 mulching disks may move freely while sup-

ported by the tires or rims of the packing disks. It will be seen that all of the stresses sustained by the mulching disks are supported by the rims of the packing disks, and on this account, and on account of the co-action and contact of these parts, the construction is considered to be durable. Since the adjacent ends of the hubs may be disposed in contact, the outwardly-projecting rims of the mulching disks will not be compressed between the A-shaped rims of the packing disks.

While the implement may have a variety of uses, it may be stated that some of the benefits to be derived thereby are, that disks 6 cause the plowed ground to be sufficiently packed to close all openings or "air-spaces" and thereby to prevent or retard evaporation; and disks 7 operate to break the smooth surface formed by the packing disks and form pockets in the crests, tending to prevent the escape of moisture from capillary attraction.

Having described the several parts of the invention, and their uses, a further expla-

nation relating to operation is not necessary.

What I claim and desire to secure by Letters Patent is,—

An implement for the purpose described, comprising, in combination with a frame and a shaft, a plurality of primary disks on the shaft, each having a transverse rim with an outwardly convergent part, secondary disks, each consisting of a peripherally toothed rim disposed between two adjacent primary disks and having a circular flange projecting transversely from one of its sides for engagement with the inner side of the rim of a primary disk, the diameter of said flange being less than that of said rim to permit its axis to be disposed in non-alinement with the axes of said adjacent primary disks.

In testimony whereof I have affixed my signature in presence of two witnesses.

LAURITZ T. RASMUSSEN.
